(57) **CLAIM**

The ornamental design for a license plate frame, as shown and described.

DESCRIPTION

FIG. 1 is a front perspective view of a license plate frame, showing our new design;

FIG. 2 is a back perspective view thereof;

FIG. 3 is a top plan view thereof;

FIG. 4 is a right side view thereof;

FIG. 5 is a front view thereof;

FIG. 6 is a bottom plan view thereof;

FIG. 7 is a front perspective view of a second embodiment of a license plate frame, with the ornament attached in a lower position than shown in FIG. 1;

FIG. 8 is a back perspective view of FIG. 7;

FIG. 9 is a top plan view of FIG. 7;

FIG. 10 is a right side view of FIG. 7;

FIG. 11 is a front view of FIG. 7;

FIG. 12 is a bottom plan view of FIG. 7;

FIG. 13 is a front view of a third embodiment of a license plate frame with the ornament located at the bottom of the frame attached in a slightly lower position than shown in FIGS. 7-12; and,

FIG. 14 is a fourth embodiment of a license plate frame with the ornament located at the top of the frame attached in a slightly lower position than shown in FIGS. 1-6.
